FORM CLAMP FOR CONCRETE FORM RODS

Theodore A. Kus, Oak Lawn, Ill., assignor to Universal Form Clamp Co., Chicago, Ill., a corporation of Illinois

Filed Oct. 30, 1961, Ser. No. 67,302

Term of patent 14 years

(Cl. D51—1)

Fig. 1.

Fig. 2.

Fig. 3.

Fig. 4.

FIGURE 1 is a perspective view of a form clamp for concrete form rods showing my new design;

FIGURE 2 is a top plan view;

FIGURE 3 is a side elevational view; and

FIGURE 4 is an end elevational view taken from the top of FIGURE 3.

I claim:

The ornamental design for a form clamp for concrete form rods, substantially as shown.
